(57) **CLAIM**

The ornamental design for a display screen or a portion thereof with a graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a view of a display screen or a portion thereof with a graphical user interface;

FIG. 1A is an enlarged partial view of FIG. 1 showing the portion of the figure surrounded by broken lines identified by FIG. 1A in the view;

FIG. 1B is an enlarged partial view of FIG. 1 showing the portion of the figure surrounded by broken lines identified by FIG. 1B in the view;

FIG. 1C is an enlarged partial view of FIG. 1 showing the portion of the figure surrounded by broken lines identified by FIG. 1C in the view;

FIG. 1D is an enlarged partial view of FIG. 1 showing the portion of the figure surrounded by broken lines identified by the FIG. 1D in the view;

FIG. 1E is an enlarged partial view of FIG. 1 showing the portion of the figure surrounded by broken lines identified by the FIG. 1E in the view;

FIG. 1F is an enlarged partial view of FIG. 1 showing the portion of the figure surrounded by broken lines identified by the FIG. 1E in the view;

FIG. 1G is an enlarged partial view of FIG. 1 showing the portion of the figure surrounded by broken lines identified by the FIG. 1G in the view;

FIG. 1H is an enlarged partial view of FIG. 1 showing the portion of the figure surrounded by broken lines identified by the FIG. 1H in the view;

FIG. 1I is an enlarged partial view of FIG. 1 showing the portion of the figure surrounded by broken lines identified by the FIG. 1I in the view;

FIG. 1J is an enlarged partial view of FIG. 1 showing the portion of the figure surrounded by broken lines identified by the FIG. 1J in the view;

(Continued)

FIG. 1K is an enlarged partial view of FIG. 1 showing the portion of the figure surrounded by broken lines identified by the FIG. 1K in the view;

FIG. 1L is an enlarged partial view of FIG. 1 showing the portion of the figure surrounded by broken lines identified by the FIG. 1L in the view;

FIG. 1M is an enlarged partial view of FIG. 1 showing the portion of the figure surrounded by broken lines identified by the FIG. 1M in the view; and,

FIG. 1N is an enlarged partial view of FIG. 1 showing the portion of the figure surrounded by broken lines identified by the FIG. 1N in the view.

The broken lines showing a display screen or a portion thereof in all views are for the purpose of illustrating environment and form no part of the claimed design. The broken lines identifying locations of each partial view of FIGS. 1A-1N in FIG. 1 are for the purpose of explaining the relative position of each partial view and form no part of the claimed design.
